UNITED STATES PATENT OFFICE.

CHARLES ANDREW REIFEL, OF NEW YORK, N. Y.

TRANSMITTER.

1,278,505.

Specification of Letters Patent. Patented Sept. 10, 1918.

Application filed November 10, 1917. Serial No. 201,317.

To all whom it may concern:

Be it known that I, CHARLES A. REIFEL, a citizen of the United States, and a resident of the city of New York, borough of Manhattan, in the county and State of New York, have invented a new and Improved 5 Transmitter, of which the following is a full, clear, and exact description.

This invention relates to sound transmitters of the microphone type especially adapted for use in audiphones and similar instruments.

The invention has for its general objects to provide a transmitter of improved construction whereby the sensitiveness is increased and sounds transmitted with fullness and loudness of tone while the transmitter is of minimum size.

A more specific object of the invention is 20 the provision of a sound box or resonant chamber formed in the body or shell of the device, whereby the range of effectiveness is increased and a more natural tone produced with fullness and loudness.

With such objects in view, and others 25 which will appear as the description proceeds, the invention comprises various novel features of construction and arrangement of parts which will be set forth with particularity in the following description and 30 claims appended hereto.

In the accompanying drawing, which 35 illustrates one embodiment of the invention and wherein similar characters of reference indicate corresponding parts in all the views,

Figure 1 is a front view of the transmitter;

Fig. 2 is a central section; and

Fig. 3 is a front view of the transmitter 40 with the outer cap removed.

Referring to the drawing, 1 designates the back of the transmitter which has removably applied thereto a cap 2, and clamped between the flange 3 of the back and annular shoulder 4 of the cap 2 is a diaphragm 5 which co-operates with the usual microphone 5' in the back 1. The cap has a shallow raised portion 6 which forms a chamber 7 45 at the side of the diaphragm opposite from

the microphone. Fitted over the cap 2 is an outer cap 8 which cooperates with the inner cap 2 to form a sound collecting chamber or resonant box 9. The face or wall 10 of the cap 8 is provided with apertures 11 by which the sound waves enter the chamber 9. By extensive experimenting it has been found that best results are obtained by having at the center of the face 12 of the inner cap a group of closely arranged apertures 13 which 55 flare outwardly or toward the openings 11, whereby the sound waves pass into the chamber 7 and strike on the center of the diaphragm. It is difficult to explain the theory by which the best results are obtained 60 through arranging the apertures in the manner specified, but fuller and louder tones 65 can be transmitted more naturally and the instrument is rendered more sensitive.

From the foregoing description taken 70 in connection with the accompanying drawing, the advantages of the construction and method of operation will be readily understood by those skilled in the art to which the invention appertains, and while I have 75 described the principle of operation, together with the device which I now consider to be the best embodiment thereof, I desire to have it understood that the device shown is merely illustrative and that 80 such changes may be made when desired as fall within the scope of the appended claims.

Having thus described my invention, I claim as new and desire to secure by Letters Patent:

1. A transmitter of the class described including a diaphragm, a back having a chamber, a microphone in the chamber, an inner cap fitted to the back and clamping the diaphragm in place, said cap being formed with 90 a chamber at the side of the transmitter opposite from the microphone, and an outer cap forming with the first-mentioned cap a resonant chamber, there being a plurality of closely arranged apertures in the central 95 portion of each cap.

2. A transmitter of the class described comprising a diaphragm, a microphone at one side of the diaphragm, and a structure in which the diaphragm and microphone 100

are mounted, said structure having a relatively shallow chamber at the side of the diaphragm opposite from the microphone, and a deeper chamber outwardly from the first-mentioned chamber and diaphragm, the wall of the outer chamber being provided with a plurality of closely arranged sound-

admitting apertures and the wall of the shallow chamber being provided with closely arranged apertures at the center which diverge outwardly toward the first-mentioned apertures. 10

CHARLES ANDREW REIFEL.
